Des. 221,441
Patented Aug. 17, 1971

221,441

SPEAKER CABINET

Haruo Ishikawa, 3-314, 1246 Matsunoki Jutaku,
Matsunoki-chi Suginami-ku, Tokyo, Japan

Filed Mar. 4, 1970, Ser. No. 21,729

Claims priority, application Japan Dec. 26, 1969

Term of patent 14 years

Int. Cl. D14—01

U.S. Cl. D26—14

FIG. 1

FIG. 2

FIG. 3

FIG. 4

FIG. 1 is a front elevational view of the speaker cabinet showing my new design;

FIG. 2 is a side view thereof;

FIG. 3 is a top plan view thereof; and

FIG. 4 is a top-front perspective view thereof.

The bottom view is identical to the top shown in FIG.

3. The side opposite that shown in FIG. 2 is identical to that shown in FIG. 2 and the rear view is plain and unornamented.

I claim:

The ornamental design of speaker cabinet, substantially as shown and described.
